J. M. LE GRAND

TRAP

Filed April 19, 1926

INVENTOR.

Joseph M. Le Grand
BY
William W. Farney
ATTORNEYS.

UNITED STATES PATENT OFFICE.

JOSEPH M. LE GRAND, OF BALTIMORE, MARYLAND, ASSIGNOR TO CARRIER ENGINEERING CORPORATION, A CORPORATION OF NEW YORK.

TRAP.

Application filed April 19, 1926. Serial No. 102,948.

The object of my invention is the providing of an improved trap in a dust-separating system.

A further object of my invention is the providing a dust trap, or separator, in which the finest particles may be removed from gaseous suspension with the minimum loss of such particles in a separation thereof with the minimum movement of said gas.

10 A further object of my invention is an improved means for the control of the movement of gases bearing solids, in a separating appliance.

15 A further object of my invention is the providing of plural separation in a step-down system of exhaust separation.

A further object of my invention is the providing of plural separation in a step-down system of exhaust separation and the 20 introduction of gas-bearing substance by a tangential admission under a diminished pressure.

25 A further object of my invention is an improved method for handling air bearing dust to extract the dust therefrom with a minimum movement of said air.

With the foregoing and other objects in view, my invention consists of the methods employed, combination and arrangement of 30 systems, apparatus and means as hereinafter specifically provided and illustrated in the accompanying drawing wherein is shown the preferred embodiment of my invention, but it is understood that changes, variations 35 and modifications may be resorted to which come within the scope of the claims hereunto appended.

In the drawing of the herein-described embodiment of my invention, Fig. 1 is a 40 sectional view in elevation of my improved dust-trap, or separator; Fig. 2 is a sectional view taken through 2—2 of Fig. 1; Fig. 3 is a sectional view taken through 3—3 of Fig. 1; Fig. 4 is a sectional view taken 45 through 4—4 of Fig. 1; and Fig. 5 is a sectional view taken through 5—5 of Fig. 2.

Similar numerals refer to similar parts throughout the several views.

1 is the outside drum, or shell. 2 is the 50 partition dividing the space within shell 1 into a plurality of compartments, as shown into compartment "A", and compartment "B". 3 is the head of shell 1 and forms the top of compartment "A". 4 is the bottom of

the shell and forms together with trap-door 55 the bottom of compartment "B".

6 is an exhaust pipe leading from the central portion of head 3 and extends some distance within "A", and the outer end of this exhaust pipe is provided with some means 60 for exhaustion not shown. 7 is an exhaust pipe in the central portion of partition 2 extending some distance within chamber "B", and also extends some distance within exhaust pipe 6. The opening, or inlet, into 65 exhaust pipes 6 and 7 are enlarged as shown at 13 and 14 respectively.

Exhaust pipe 6 is provided with some means for regulating the movement of gases therein, such as, a damper or other means, 70 as shown at 15 in Fig. 4, likewise, pipe 7 is provided with a damper or regulating means 16, as shown in Fig. 4. 17 is a hand hold.

In partition 2 is a slit 8, the edges 9 and 75 10 of which are shown in Fig. 5 and are adjusted with reference to each other and the movement of the gas in chamber "A" so as to permit the desired diversion or deflection of the gas into chamber "B".

11 is the inlet pipe entering chamber "A" 80 preferably tangentially, as shown in Fig. 2. 5 is the bottom trap-door, or dumping means.

The operation of my invention is as follows:

85 Inlet pipe 11 is attached so as to collect and convey the gas suspended matter into the separator tangentially so as to cause a whirl within the same the centrifugal motion of which throws the heavier particles in suspension to the periphery and gravity tends to draw the same downward, thus we get the gas super-loaded in the outer and lower portions of chamber "A". At this point slit 8 takes the heavier portion slicing 90 it as it were from the bottom of the whirling mass, and deflects it into chamber "B".

95 Exhaust pipe 6 is so connected as to convey the gas relieved of its load where desired, preferably through an exhausting 100 means, such as an exhaust blower. The matter extracted from the conveying gas is removed through the bottom trap-door or dumping means 5.

105 The creation of a partial vacuum, or diminished pressure, in exhaust pipe 6 causes an inflow therein from compartment "A" and also an inflow through exhaust pipe 7

concentric within the same. The ratio between the said two pipes being determined by the relative sizes of the said two pipes, their inlet orifices and dampers controlling the same, and the slit 8, or other openings, between compartments "A" and "B", this is adjusted by means of dampers 15 and 16 through hand-hold 17.

The gas in entering compartment "B" 10 through slit 8 is suddenly reduced in velocity to almost a quiescent state, and the suspended matter is allowed to settle. The large opening of pipe 7 facilitates this. To withdraw the deposited matter the movement of 15 the gas is stopped and trap-door 5 is opened, thus allowing the solid matter or sediment to descend.

Having thus described my invention, what I claim and desire to secure by Letters Patent is:

1. A plurality of separating chambers one chamber of which is provided with means for rotating gas admitted thereto so as to

sweep the interior surface thereof, a break in the floor of said surface to interrupt the 25 gas in proximity thereto to cause the same to flow into the other of said chambers through means provided, and means for exhausting gas from said two chambers consisting of a unified exhaust comprising an 30 exhaust from each chamber connecting into a single exhaust.

2. A plurality of separating chambers one chamber of which is provided with means for rotating gas admitted thereto so as to 35 sweep the interior surface thereof, a break in the floor of said surface to interrupt the gas in proximity thereto to cause the same to flow into the other of said chambers through means provided, and means for exhausting 40 gas from said two chambers consisting of a unified exhaust comprising an exhaust from each chamber connecting into a single exhaust and means for regulating the relative exhaust from said two exhausts.

JOSEPH M. LE GRAND.
